Inventor:

UNITED STATES PATENT OFFICE.

JOSEPH A. RAYMOND, OF CHICAGO, ILLINOIS.

HANDLE-BAR BRACKET AND ESCUTCHEON.

1,232,084.

Specification of Letters Patent.

Patented July 3, 1917.

Application filed October 27, 1916. Serial No. 128,097.

To all whom it may concern:

Be it known that I, JOSEPH A. RAYMOND, a citizen of the United States, and a resident of Chicago, in the county of Cook and State 5 of Illinois, have invented certain new and useful Improvements in Handle-Bar Brackets and Escutcheons, of which the following is a specification.

This invention relates to handle bar brackets and escutcheons joined thereto.

In the making of burial caskets it is deemed necessary to provide handle bars for the convenience of bearers at funereal functions; and to so construct said handle bars 15 and so attach them to the casket, that a massive and presentable appearance is obtained, and requisite strength and certainty of operation is assured.

And the object of this invention is to obtain 20 a handle bar bracket or hanger arm and escutcheon which are pivotally joined, which are not liable to become separated, either by the breaking or the loss of any of the parts thereof; and to obtain a device which is not 25 liable to get out of order, which is durable, which is economically made; and of good appearance when properly attached to a casket.

In the drawing which accompanies and 30 forms a part hereof,

Figure 1 is a front elevation of a bracket arm and an escutcheon;

Fig. 2 is a section on line 2—2 of Fig. 1, viewed in the direction indicated by the 35 arrows;

Fig. 3 is a section on line 3—3 of Fig. 2, viewed in the direction indicated by the arrows;

Fig. 4 is a developed view of the blank 40 from which the bracket is obtained; and

Fig. 5 is a plan view of a portion of the blank from which the escutcheon is obtained, showing particularly the manner in which the ears to which the bracket is pivoted are obtained.

A reference character applied to designate a given part is used to indicate said part throughout the several figures of the drawing wherever the same appears.

50 A is an escutcheon the body whereof is forced outward from the plane of its contour line to obtain a spaced distance between said body part and the surface of the casket, trunk, chest, or other thing to which 55 said escutcheon is secured, as is well represented in the drawing. B, B, are ears be-

tween which the bracket or hanger arm, (about to be described) is pivotally attached. The ears B are obtained by cutting aperture C, (see Fig. 5), thereby obtaining projections b, having apertures D therein, and said projections being bent out from the body part of the escutcheon and backward into planes which are at right angles to the face of said body part, on substantially the 60 broken lines b¹, form said ears B. E is a bracket or hanger arm, which is obtained from the blank illustrated in Fig. 4, by bending the projections or wings e substantially on lines e¹, into a plane at right angles to the 65 remainder of said blank; bending the portion extending between broken lines E¹ and E² into form, or shape, to fit a handle bar; making an additional bend on line E² to bring the recesses F adjacent to projections f, and bending said projections over and down upon part E³ of the blank, (see 70 Fig. 2.).

The handle bar which is indicated by broken lines in Fig. 1, and lettered X¹, is 75 cylindrical, and fits in aperture X.

G are projections on and near one end of wings e, which form ears adapted to come adjacent to and between ears B, when the end of the bracket or hanger arm E is inserted in aperture C of the escutcheon so 85 that the apertures g and D are concentric.

The portion of the ears G between aperture g and broken line H is then forced outward into cylindrical shape, (h), entering 90 the aperture D in ear B; and forming the pivots on which said bracket is rotatably movable.

When the bracket is moved around on said 95 pivotal parts h, from the position thereof which is illustrated in full lines in Figs. 1 and 2, into the position which is indicated by broken lines in Fig. 2, the upper or outer face of said bracket, on the line which is indicated by the letter I, in Fig. 2, is forced 100 into contact with the upper edge C¹ of aperture C; and further upward or rotatory movement of the bracket is thereby prevented.

The load carried by the device, when constructed and operated as above described, is 105 on the pivotal part h and the meeting edge C¹ of aperture C, and the face of the bracket at I. It will be observed that no pintle or pin is required to pivotally join the bracket 110 E to escutcheon A.

J are apertures in the escutcheon, through

which ordinary wood screws extend into the side walls of the casket to which the escutcheon is to be secured.

5 *j* is an aperture in the cylindrical part of the bracket, through which a pin or screw is extended to secure the handle X^1 in aperture X .

The drawing discloses that the edges of the blank from which the escutcheon is obtained are in planes at right angles to the face of the body part of the blank, the width of said edges being the thickness of the metal; while in the escutcheon itself said edges are in one plane and the body of the escutcheon is advanced from said plane to permit the hanger arms to be pivoted so far back of said body that the upper edges of the apertures through which said hanger arms extend form abutments which resist the upward thrust of said hanger arms when turned into substantially horizontal planes.

I claim:—

A two piece handle bar comprising a bracket member and an escutcheon member,

Copies of this patent may be obtained for five cents each, by addressing the "Commissioner of Patents, Washington, D. C."

said escutcheon member consisting of a sheet 25 metal base with the edges thereof in one plane and the body part forward of said plane, said body part provided with an aperture therethrough and backwardly extending ears on the sides of said aperture integral with said body part, and said bracket member formed of sheet metal provided with ears, all of said ears adapted to be arranged in substantially parallel planes, the ears of one of said members provided with 30 apertures and a portion of the ears of the other of said members forced into cylindrical form fitting and rotatably movable in said last named apertures to form pivots, said bracket and said aperture in the escutcheon arranged so that the upper edge 35 of the aperture limits the rotation of the bracket on said pivots.

JOSEPH A. RAYMOND.

In the presence of—

CHARLES TURNER BROWN,
J. SCUDDER.
